United States Patent Office

Des. 195,554
Patented July 2, 1963

195,554

TILE

Donald R. Speaker, North Hollywood, Calif., assignor to Pomona Tile Manufacturing Company, Los Angeles,
Calif., a corporation of California

Filed July 12, 1962, Ser. No. 70,895

Term of patent 14 years

(Cl. D18—2)

FIG. 1.

FIG. 2.

FIG. 3.

FIG. 4.

FIG. 5.

FIG. 6.

The undisclosed rear is substantially plain.

I claim:

The ornamental design for a tile, substantially as shown and described.
